UNITED STATES PATENT OFFICE.

CHESTER C. SMALL, OF NEWTON, MASSACHUSETTS, ASSIGNOR, BY MESNE ASSIGNMENTS, TO THE UNITED SHOE MACHINERY COMPANY, A CORPORATION OF NEW JERSEY.

NAIL-ASSORTING MECHANISM.

SPECIFICATION forming part of Letters Patent No. 707,141, dated August 19, 1902.

Application filed July 2, 1898. Renewed February 3, 1900. Serial No. 3,907. (No model.)

To all whom it may concern:

Be it known that I, CHESTER C. SMALL, of Newton, county of Middlesex, State of Massachusetts, have invented an Improvement in 5 Nail-Assorting Mechanism, of which the following description, in connection with the accompanying drawings, is a specification, like letters on the drawings representing like parts.

10 This invention is intended as an improvement on the class of nail-assorting mechanism shown and described in United States Patent No. 577,213, dated February 16, 1897. That patent shows and describes a nail-controller having a series of pockets side by side which are entered by a series of nails, the said nails leaving the ends of a series of raceways indiscriminately points and heads first and being by a movement of said controller 15 all put in said pockets with their heads standing in the same direction, so that by a final circular or rotative movement of said controller all said nails may be discharged from said pockets with their points all in the same 20 direction.

25 In the mechanism herein shown as embodying my present invention I have done away with the circularly-moving nail-controller, and instead of it I employ a throat having a 30 series of nail-passages to lead the nails at the proper time into chutes or nail-conducting tubes, there being one passage for each raceway. The nails on their arrival at the end of the raceway meet an arresting device or stop, 35 herein represented as a notched slide-bar provided with a series of horizontally-extended rests. Each of these rests sustains one end of a nail while its opposite end still rests on the raceway, and said arresting device or stop is 40 moved to bring its notched parts under the nails, permitting the head-first nails to drop by gravity each into a passage of the throat, the point-first nails entering the notches in 45 the stop and meeting a gage, at which time the heads of those nails leave the raceway, and they immediately drop head first each into its proper passage in the throat, all the nails thus entering the throat head first. The 50 series of notches in the stop are so located

that the notches are out of line with the raceways that supply the nails and out of line with the nail-receiving grooves of the throat, the unnotched or plain portions of said stop being at such time in line with the raceways 55 to stop the nails leaving the ends of the raceways. The stop has at its edge next the ends of the series of raceways a series of horizontally-extended rests, said rests being separated by suitable spaces, each rest standing 60 when said stop is in its normal position in line with the grooves at the ends of the raceway and at substantially the level of the bottoms of said grooves, so that the points and heads of said nails arranged indiscriminately and leaving said grooves pass over the 65 rests and meeting said stop lie on the rests. Now to effect the discharge of these nails so sustained with their heads and points arranged indiscriminately I slightly move 70 the stop longitudinally, causing the rests to pass from under all the nails lying thereon. The head-first nails immediately respond to gravity and drop head first into the passages of the throat; but the point-first nails remain 75 with their heads resting on the raceways and their points opposite notches b^2 of the stop. The point-first nails immediately slide into 80 said notches until they meet a gage so located as to permit the heads of those nails to leave the raceway, when they also drop into the passages of the throat head first. The gage prevents the escape of the nails directed point first across said throat, and the said gage will 85 in practice be adjusted according to the length of the nails used.

One part of my invention therefore consists in an arresting device or stop adapted to arrest temporarily a series of nails with their heads and points arranged indiscriminately, which may be moved to effect the discharge of said nails with their heads all in one direction.

Other features of my invention will be hereinafter more particularly set forth and made 90 the subject of claims at the end of this specification.

Figure 1 is a partial top or plan view of a nail-assorting mechanism embodying my invention. Fig. 2 is a face view of the parts 95 100

shown in Fig. 1. Fig. 3 is a left-hand end view of the parts shown in Fig. 1. Fig. 4 is a section in substantially the dotted line x , Fig. 2. Fig. 5 is a detail to be referred to. Fig. 5 6 is a detail showing part of the bar b .

In the drawings the framework A , the series of raceways c^x , the lifter f , normally occupying a position in line with the raceway and provided with a series of grooves to correspond with the grooves of said raceways, the said lifter when in its normal lowered position receiving upon it the endmost nails of the series of nails in said raceways, the ends of the nails, whether heads or points leading, contacting with a shoulder f^x ; the rod f' , connected with said lifter and surrounded by a spring f^3 ; the cam f^2 to act on said rod and elevate said lifter, so that the series of nails held in its grooves may be lifted, the nails sliding therefrom through a series of grooves in the delivery end h of the said raceways, said delivery end being composed of a bar having a series of grooves, one for each groove of the raceway, said bar being adjustably sustained by a suitable adjusting-nut h^{10} , so that it may be adjusted to the right or left, (viewing Fig. 4,) according to the length of the nail being used, are and may be all substantially as shown and described in United States Patent No. 577,213. The cam f^2 is fast on a shaft e , said shaft having upon its end which is broken off in Fig. 4 a suitable clutch—such, for instance, as that shown in said patent—which may be engaged at times intermittently with a coöperating clutch part which is rotated continuously. The shaft e is rotated once and then stopped, the rotation of the shaft being controlled either by a manual operation or by the operation, say, of some moving part of a heel-nailing machine, as provided for in United States application, Serial No. 625,873, filed March 3, 1897, with which class of heel-nailing machine this assorting apparatus is adapted to be used.

In the mechanism herein shown as embodying my present invention the shaft e , as provided for in said patent, will carry at its front end a collar having a stud or projection e^{10} , behind which will rest an arm m^4 . When the arm m^4 is down in its normal position, it coöperates with the projection e^{10} of the said collar to effect the disengagement of the clutch; but when the said arm m^4 is elevated to release said projection a spring e^{12} , inside the shaft e , bearing at one end upon a stationary abutment e^{13} , will act to effect the engagement of the clutch, and when the said shaft has completed a rotation the stud or projection of the collar will act again upon the side of the arm and gradually draw the clutch out of engagement, leaving the shaft e at rest. This clutch part herein referred to is not herein fully illustrated, because it is not a part of my present invention.

The framework A has suitable stands A' , which receive the journals of a throat A^2 , herein represented as a piece of metal having

a series of passages a arranged side by side, a passage for each raceway-groove. (Shown in Fig. 4.) Said passages are separated by the walls m . (Shown in full lines in Fig. 1.) The throat has extended from it a rod a^2 , upon which is adjustably mounted a collar a^3 , adapted to be held in adjusted position by a set-screw a^4 . This collar has secured to it by screw a^5 an adjustable gage a^6 , shown as provided with an upturned lip standing transversely of the ends of the raceway-grooves, the said gage being adjustable toward and from the end pieces h of the raceways, according to the length of nail being used. The throat A^2 is herein shown as provided at its upper edge, alongside the said series of passages a , with a dovetailed groove, (see Fig. 4,) which receives a correspondingly-shaped tongue projecting from the under side of a stop or slide bar b , (shown in Figs. 1 and 4 and partially in Figs. 2 and 3,) having a series of upright projections b' , with notches or spaces b^2 between said projections, the edge or face of said stop at its side toward the ends of the raceways or their grooves having a series of rests b^3 , (shown in Figs. 1 and 4,) said rests having between them spaces b^4 . (Shown in dotted lines in Fig. 1 and in full lines in Fig. 6.) This stop has, as shown, a screw stud or pin b^5 , (see Fig. 5,) against which acts one end of a spring b^6 , arranged in a pocket in the throat A^2 . This spring acts normally against said stud to keep the stop b pressed toward the left, (viewing Figs. 1 and 5,) with the said pin b^5 against a slide rod or pin b^7 , the end of which is exposed at the end of the throat, and in this normal condition of the stop the rests b^3 stand in line with the passages a and with the grooves in the raceway end piece h , the said rests standing, preferably, somewhat below the level of the bottoms of the said grooves, as represented in Figs. 1 and 4. In this condition of the parts (viewing Fig. 1) it will be noticed that the projections b' of the stop stand opposite the grooves of the end piece h , so that all the nails leaving the end piece h are stopped by the projections b' , and each nail has its head or point supported by one of the rests b^3 .

Having now, as will be understood, collected in line a series of nails arranged head and point first indiscriminately, with their heads and points lying on the rest b^3 , to effect the discharge of all the nails into and through the passages a head first I have only to move the stop b to the right, (viewing Figs. 1 and 2,) and in such movement the rests b^3 retire from under the nails, so that the head-first nails, as their heaviest parts are off the raceway, immediately drop by gravity into the passages a underneath them; but the point-first nails remain supported by their heads in the ends of the grooves in the end piece h , and consequently they cannot drop; but as the said stop b is moved to the right the notches therein are brought into line with the grooves of the end piece h , and therefore the point-first

nails slide quickly from the end piece and enter the notches b^3 of the stop b , and their points are stopped by the gage a^6 , which checks any further movement of the nails, so 5 that the nails tip down head first into the said passages, and thus all the nails are delivered into the passages a head first.

To move the stop b to effect the discharge of a series of nails, I have in this instance 10 employed an upright lever, as c , pivoted at c' on a stud c^2 , extended from the framework. Said lever at its upper end is in engagement with the rod b^7 and has at its lower end a cam-face c^8 , adapted to be acted upon by a projection c^4 of a lever c^{40} , which when the rod c^5 is 15 lifted to enable the pin or projection c^4 , carried by said lever c^{40} , to meet the arm m^4 , before referred to, to start the shaft e , will move the upper end of said lever to the right, (viewing Fig. 2,) sliding the stop b in order that it may operate as described.

The end plate h of the raceway is mounted, as represented, on a bar h^{12} , (see Fig. 4,) which is extended across the arm at right 20 angles to the raceway. The under side of this bar h^{12} has attached to it by suitable screws an apron h^{14} , upon which any nails that escape from the raceway may drop, said nails passing from said apron into a box h^{15} , connected in suitable manner with the series of 25 main raceways.

One end of the lifter f has secured to it by suitable screws e^3 (see Figs. 1 and 3) a plate e^4 , that carries a stud-screw e^8 , upon which 30 is mounted a lever e' , a spring e^2 acting on one end of said lever to normally keep its other end against the screws e^3 .

On one of the stands A' is a headed stud g , surrounded by a spring g' . This stud receives upon it a bar-stop g^2 , Figs. 3 and 5, and the spring is so connected with said stud that it has a tendency to turn it axially, and with it the bar-stop, so that the bar-stop when 40 the rod b^7 has been acted upon to move the stop b to the right (viewing Fig. 1) to effect the discharge of nails drops, immediately after the lifter f descends, below the endmost rest of the stop b . The bar-stop holds the stop b in such position until the lifter f is again 45 raised with a new lot of nails, whereupon the end of the lever e' acted upon by the spring e^2 meets the lug g^3 of the bar-stop g^2 and lifts it in opposition to the spring g' . The spring b^6 may now act to restore the stop b into its 50 normal position, so that as the lifter arrives in its elevated position to let the nails just raised by it pass into the grooves of the end piece h the stop will be in position to arrest, as before described, the heads and points of 55 the nails. The nails leaving the passages a of the throat drop into the tops of the chutes n and pass out through the tubes n' .

It will be understood that the raceway will have co-operating with it a suitable or usual 60 device for agitating the same, so that the tendency of the nails in the grooves thereof will always be to travel down the raceway.

Having described my invention, what I claim, and desire to secure by Letters Patent, is—

1. In a nail-assorting apparatus, the following instrumentalities, viz: a throat having a series of nail-passages, raceways leading nails to said passages, and a stop having a series of rests to support temporarily the heads of those 75 nails which leave the raceways head first, and means to move said stop to remove said rests from under the heads of said nails, letting said nails, under the action of gravity, drop head first into said nail-passages, substantially as described.

2. In a nail-assorting apparatus, the following instrumentalities, viz: a throat having a series of nail-passages, and nail-receiving grooves in alignment with said passages, raceways leading nails into said nail-receiving grooves, and a stop having a series of grooves, the said stop normally occupying a position to close the said nail-receiving grooves, a gage, and means to move said stop to bring 90 its grooves in line with the nail-receiving grooves of the throat, thus permitting the nails resting point first against said stop and lying in the said nail-receiving grooves to move longitudinally under gravity and meet 95 the gage, the heads of such nails leaving the ends of the raceways and said nails under the action of gravity entering said nail-passages head first, substantially as described.

3. In a nail-assorting apparatus, the following instrumentalities, viz: a throat having a series of nail-passages, a stop having a series of notches and a series of rests, a raceway having a series of grooves to lead nails into 100 said nail-passages, the heads of those nails leaving the raceway head first coming upon and being supported by said rests, the series of nails leaving said raceways point first bearing by their points against said stop between its notches, means to move said stop 105 to remove said rests from under the nails arrested thereby head first, and to bring the notches of said stop opposite the ends of the nails directed point first to let said nails enter 110 said notches, said nails by the act of entering said notches removing their heads from the said raceways, thereby permitting their heavier heads, while their points are temporarily supported, to turn down by gravity 115 into the nail-passages, thus effecting the delivery of all of said nails through the passages of said throat head first, substantially 120 as described.

4. In a nail-assorting apparatus, a throat having a series of passages, a stop having a 125 series of surfaces co-operating with each of said nail-passages, said stop having notches between the said surfaces, means to move said stop, and a gage to arrest the ends of those nails passing through said notches, substantially as described.

5. In a nail-assorting apparatus, a throat having nail-passages, and a movable stop having 130 projections and rests and notches, said

- projections and rests sustaining respectively the points and heads of nails coming to said stop point and head first, combined with means to move said stop to remove the rests 5 from under the heads of nails arranged head first and bring the notches of said stop opposite the points of the nails arranged point first, whereby the nails arranged head first no longer supported by said rests drop into said 10 nail-passages and the nails arranged point first slide into said notches so that their heads may preponderate and enable them to drop head first into said nail-passages, substantially as described.
- 15 6. In a nail-assorting mechanism, raceways to receive and guide nails with their heads and points arranged indiscriminately, a device to arrest and sustain temporarily all the nails before they leave the raceways, and 20 means to actuate said device to deliver all the nails pointing the same way.
7. In a nail-assorting mechanism, raceways to receive and guide a series of nails, a series of passage-ways for the reception of said nails, 25 a stop presenting an upright wall and a laterally-extended notched rest, a portion of said rest normally standing in the upper part of each of said passages to sustain the head ends of the nails passing from the raceways head 30 first, and means to move said stop to put a notch at one side of a rest under the head of the nail that said head may drop through said

notch and permit the nail to enter the passage.

8. In a nail-assorting mechanism, raceways 35 to receive and guide a series of nails, a series of passages to receive said nails, a device having a series of projections separated by notches, said projections normally obstructing the entrance of point-first nails into said 40 passages, and means to move said device to put a notched part thereof in line with the points of the nails which rest against said projections and are yet sustained by their head ends in said raceway, permitting the 45 said point-first nails to enter said notches and slide therein sufficiently to enable the head ends of said nails to leave said raceways.

9. In a nail-assorting mechanism, raceways to receive and guide nails with their heads 50 and points arranged indiscriminately, a device to arrest all the nails before they leave the raceways, and means to move said device to allow the head-first nails to drop from the raceways and to allow the point-first nails to 55 travel on said device until their heads leave the raceways.

In testimony whereof I have signed my name to this specification in the presence of two subscribing witnesses.
